APPARATUS FOR THE CONTROL OF HIGHWAY CROSSING SIGNALS

Arba G. Williamson, Carnegie, Pa., assignor to
The Union Switch & Signal Company, Swiss-
vale, Pa., a corporation of Pennsylvania

Application June 27, 1930. Serial No. 464,205

29 Claims. (Cl. 246—130)

My invention relates to apparatus for the control of highway crossing signals, and has for an object the provision of means controlled by a train approaching a highway for starting the operation of the signal at substantially the same interval of time before the train reaches the highway regardless of the speed of the train.

In highway crossing signals, it is customary to provide that a highway signal shall display a danger warning when the approaching train reaches a point at a fixed distance from the highway. With this fixed point located far enough away from the highway so that the warning signal is displayed for a sufficient length of time for a train traveling at a high rate of speed, then the warning signal is displayed so long for a slow moving train that the warning signal becomes irksome to those using the highway, with the result that the warning signal may be disregarded altogether.

In providing means to insure that the operation of the warning signal is substantially of the same interval of time before the train reaches the highway, regardless of the speed of the train, it becomes necessary to not only consider the case of a train traveling at a uniform rate of speed, but also to consider the case where the approaching train changes its speed as it approaches the highway. Furthermore, it is necessary to provide that when a train is making switching movements in the vicinity of the highway, there is not a continuous operation of the warning signal; that is to say, the signal must not indicate the approach of a train when no train is about to cross the highway.

I will describe one form of apparatus embodying my invention, and will then point out the novel features thereof in claims.

The accompanying drawing is a diagrammatic view showing one form of apparatus embodying my invention.

The reference characters R and R¹ designate track rails over which traffic normally moves in a direction as indicated by the arrow and which are intersected by the highway H, shown at the right-hand end of the figure. At the intersection there is provided a highway signal S indicated on the drawing by the symbol commonly used in the art to designate an electric bell; it will be understood however, that any of the common forms of highway signals can be used.

The rails R and R¹ are divided by the usual insulated joints to form two track sections 1—2 and 2—3, which sections are traveled suc-

sively by the train as it approaches the highway and which are to be approximately equal in length. The section 2—3 is divided into sub-sections 2—2^a, 2^a—2^b and 2^b—3. The section 1—2 is provided with a track circuit which includes a track battery 4 and a track relay H¹. At the point 2^a of the section 2—3, an insulated joint 5 is inserted in the rail R¹ and a relay H³ is connected to the rail on opposite sides of the insulated joint 5. At the right-hand end of the sub-section 2^a—2^b, a battery 6 is connected across the rails, while at the left-hand end of the sub-section 2—2^a a track relay H² is connected to the rails. Current will therefore flow from the battery 6, down the rail R, through the relay H², back through rail R¹, around the insulated joint 5 by way of the coil of relay H³, and then to battery 6. With this section of track unoccupied, the normal flow of current from the battery 6 is sufficient to energize the track relay H² so that its armature contacts 7 and 8 are in the raised positions as shown in the figure, but this normal flow of current is not sufficient to energize the relay H³ so as to lift its armature contacts 9 and 10. With a train occupying the sub-section 2—2^a so as to shunt the resistance of the relay H², then the current flowing from battery 6 is materially increased and with this increased flow of current, the relay H³ is then sufficiently energized so that its armature contacts 9 and 10 will be raised into engagement with the contacts 12 and 13, respectively. As soon as the train passes the point 2^a, the current will be shunted away from the relay H³ and its armature will drop. The sub-section 2^b—3 is provided with a track circuit including a battery 14 and a relay H⁴. While as stated above, the sections 1—2 and 2—3 are to be approximately equal in length, the sub-sections 2—2^a, 2^a—2^b and 2^b—3 are not equal and may be varied to suit conditions.

The highway signal S is under the direct control of a line relay L, and is operated by a circuit consisting of the elements: battery terminal B, pack contact 15 of relay L, armature 16 in its down position, wire 17, coil of the signal S, to battery terminal C. The relay L is under the joint control of the track relays H², H³, H⁴, a time measuring device designated as a whole by the reference character A, and a device designated TH.

The time measuring device A consists of a shaft 18, shown diagrammatically as a dotted line, on which are rigidly mounted the three cams C¹, C², C³, and a disc 19. The device also comprises a dynamotor G—M mounted on a

shaft 11 which carries a disc 20 in frictional engagement with the disc 19, so that operation of the motor M causes operation of the shaft 18. It will be understood that other forms of gear reduction may be employed between the shafts 11 and 18. The complete movement of the cam shaft 18 is assumed to be 180° , and the gear reduction is to be such that it requires approximately 120 seconds operation of the motor M to make this 180° movement of the shaft 18. The normal position of the shaft 18 with cams C¹, C² and C³ is that shown in the figure, while the position 180° counterclockwise from the position shown, is the reverse position.

15 The cam C¹ operates the contacts 23 and 29, and with the cam C¹ in the position as shown so that the notch 44 comes opposite the operating arm 45 of contact 29, the arm 45 is pulled to the right by the action of the spring 46 to thereby open the contact 29. As the cam C¹ starts to rotate in the counter-clockwise direction from its full normal position, the arm 45 is at once forced to the left by the cam to close contact 29. With the cam C¹ rotated 180° , that is, to the full reverse position, and the notch 44 opposite the arm 47 of the contact 23, the spring 48 will pull arm 47 to the left to open contact 23.

20 The cam C² operates the contacts 51 and 53, and as the cam is moved away from its normal position, the spring 50 will at once pull the arm 49 to the left, to open the contact 51. The cam C² is so positioned that after 30° movement, that is, twenty seconds operation of the motor M, it forces the arm 52 to the left against the action 25 of the spring 92, to close the contact 53, and contact 53 then remains closed for the remaining portion of the movement. The cam C³ operates the contact 55 and is so positioned as to close the contact from about 5° from the normal position 30 to about 20° from normal. In this description, I shall refer to the movement from the normal position to the reverse position of the device A as a forward movement and the movement from the reverse position to the normal position as a 35 backward movement.

40 The armature of the motor M of the dynamotor is supplied with current from a battery 21 along the wire 22, contact 23 of the cam C¹, wire 24, front contact 25 of a relay AR to be described later, armature 26, wire 27, motor M, and wire 28 back to battery, or it may be supplied by current from the battery 21 along wire 22, contact 29 of cam C¹, wire 30, back contact 31 of relay AR, armature 26 in its down position 45 and as before traced.

46 The field winding 36 of the motor M is supplied with current from the battery 21 along wire 22, contact 23, wire 24, wire 32, front contact 33, armature 34, wire 35, field 36, wire 37, armature 38, front contact 39 and wires 40 and 28 to battery 21, or field winding 36 may be supplied with current from battery 21 along wire 22, contact 29, wire 30, contact 41, armature 38, wire 37, field 36, wire 35, armature 34, back contact 42 and wires 40 and 28 to battery.

50 Thus, it will be seen that with the relay AR energized and the contact 23 closed, current is supplied to both the armature and the field winding of the motor M and that with the relay AR deenergized and the contact 29 closed, the current is likewise supplied to both armature and field of the motor M, but, in this latter case, the direction of current through the field 36 is reversed to that in the first case. Thus, with the 55 relay AR energized and contact 23 closed, the

motor rotates in a direction to cause the shaft 18 and the cams to be moved through the forward movement, while with relay AR deenergized and contact 29 closed, the rotation of the motor M is such as to produce the backward movement of the shaft and cams. 80

The relay AR is normally deenergized and is energized by a circuit from battery B along wire 56, contact 51 closed only when cam C² is in normal position, wire 57, coil of relay AR, wire 58, back contact 59, armature 60 in its down position, wire 61, contact 62 of relay H², armature 7, and to common battery. The relay AR is provided with a stick circuit which passes from battery terminal B, through wire 63, contact 64 of relay AR, winding of the same relay, and then as before to battery terminal C. With the track section 1-2 occupied so as to shunt the relay H¹ and the timing device A, occupying its full normal position, the relay AR is energized and once energized it will be retained energized through its stick circuit until the relay H² is deenergized or the relay H¹ again reenergized. 85 90 95

The generator end G of the dynamotor G-M is designed to deliver the same voltage as that 100 of the line battery (not shown) used with my invention and which is commonly taken as 10 volts, and the generator G is of sufficient capacity so that it will deliver current to readily energize any relay that may also be energized 105 by the line battery. A relay K is associated with the time measuring device A, the energizing circuit for which relay is from the positive terminal of the generator G along wire 65, contact 55, wire 66, coil of relay K, wire 67, back 110 contact 68 of relay H², armature 7, common wire, wire 69, armature 70 of the relay AR, back contact 71 and wire 72 to the negative terminal of generator G. Thus with the time measuring device A moving from the reverse position to its 115 normal position so that the contact 55 is closed for a period and with the relay H² shunted, the relay K will be energized by current from the generator G and the relay K will then be held energized by the stick circuit consisting of battery terminal B, wire 73, armature 74, front contact 75, coil of relay K, wire 67, contact 68, armature 7 and the common battery terminal. 120

The relay TH is a thermal relay and may be one of any of the types well known in the art 125 and it is designed to close its contact 76 a predetermined interval after its energizing circuit is closed, and in this description, it will be considered that the contact 76 is closed only after the relay TH has been energized for a period of 130 twenty seconds. The energizing circuit for relay TH consists of battery terminal B, armature 9 of relay H³, contact 12, wire 77, relay TH, wire 78, armature 80 of a stick relay ST about to be referred to, back contact 79 and common battery. 135 Associated with the relay TH is the stick relay ST, the energizing circuit of which consists of battery terminal B, contact 76 of relay TH, wire 81, coil of relay ST and the common battery. The stick circuit for this relay ST consists of 140 generator G, wire 65, contact 53, wires 93 and 84, contact 85, wire 86, coil of ST, common wire, wire 69, armature 70, contact 71 and wire 72 to generator G. In the event the relay K has been picked up in the manner above described 145 then this stick circuit of ST is supplied with current from battery terminal B, armature 82, contact 83, wire 84, contact 85, wire 86, relay ST and to common battery.

150 Normally the line relay L is energized by a

circuit from the battery terminal B along contact 87, armature 8 of relay H², wire 89, armature 90 of the relay H⁴, wire 91, coil of relay L, and to common battery. A second circuit for energizing the relay L consists of generator G, wire 65, contact 53, wire 93, wire 84, wire 94, contact 13 of the relay H³, armature 10, wire 95, wire 89, armature 90, wire 91, coil of relay L, common wire, wire 69, armature 70, contact 71 and wire 72 to generator G. Furthermore, there is a by-pass for this last circuit around the contact 13 which consists of wire 96, branching from the wire 93, armature 97 of the stick relay ST and wire 98 to the wire 89. Furthermore, the relay L can be supplied with current from battery terminal B along wire 73, armature 82 of the relay K, contact 83, wire 84 and then by either the path through the contact 13 of relay H³ or by the path through the contact 97 of the stick relay ST.

In describing the operation of my device, I shall assume that the highway signal S is to display a warning signal for a period of twenty seconds upon the approach of a train, and I shall assume that the sections 1-2 and 2-3 are each approximately 2640 feet in length, that the sub-section 2-2^a is 380 feet in length, and that the sub-section 2^b-3 is about 440 feet in length. Taking the maximum speed of a train to be ninety miles per hour, then as such a train enters the section 1-2 and shunts the relay H¹, the device A will start on its forward movement. As soon as the device A leaves the full normal position, the contact 29 will be closed and at the end of twenty seconds, the contact 53 will be closed. However, if the train is traveling ninety miles per hour it will require only twenty seconds, to travel the entire section 1-2, and the train upon entering the section 2-3 shunts the relay H², which deenergizes the relay AR thereby reversing the motor M so that the backward movement of device A is started, that is to say, the device A is reversed from its forward movement to its backward movement just before it has reached the point where the contact 53 is closed. As the train shunts out the relay H², it opens the circuit to the line relay L at the point 87 and as there is no other circuit closed whereby relay L can be energized, the highway signal S is rendered active to display a warning signal as soon as the train enters the section 2-3 and will remain active as the train travels this section. Inasmuch as the train is traveling at ninety miles an hour, it will travel the section 2-3 in twenty seconds, thus the highway signal is displayed for twenty seconds before the highway is crossed by the train.

Let us now assume that the train is traveling at a speed of sixty miles per hour and thereby takes thirty seconds in traveling the section 1-2. As before, the time measuring device A starts on its forward movement as soon as the train enters the section 1-2 and will continue in its forward movement until the time the train enters section 2-3 and shunts relay H², which is thirty seconds. With device A making a thirty second forward movement, the contact 53 has been closed during the last ten seconds and it will remain thus closed for the first ten seconds of the backward movement. Thus as the train enters section 2-3 and shunts relay H² to open the circuit of relay L at contact 87, current is supplied from the generator G through the contact 53 to the wire 89 leading to

the relay L by way of the contact 13 for a period of ten seconds. As the train is traveling sixty miles an hour it will require thirty seconds to travel the section 2-3, and therefore the signal S is displayed again for a period of twenty seconds before the train reaches the highway.

Let us next take the case of a slow moving train having a speed of fifteen miles per hour and thereby requiring 120 seconds to travel the section 1-2. The device A will thus make a complete forward movement before it is reversed by the deenergizing of relay AR and started on its backward movement, and the contact 53 will this time be retained closed for a period of one hundred seconds after the train enters section 2-3. While the train is traveling from 2 to 2^a, the circuit from the generator G to the relay L is through the front contact 13 of the relay H³, and as soon as the train reaches the point 2^a and shunts relay H³, current is supplied then to the relay L from generator G by way of the contact 97 of the stick relay ST, inasmuch as the train moving fifteen miles per hour requires forty seconds to travel from 2 to the point 2^a and relay TH has ample time to close its contact 76 thereby energizing the stick relay ST. The result is that current is supplied from generator G to the relay L for a period of one hundred seconds after the train has passed the point 2, and therefore the highway signal S will not become active until just as the train enters the sub-section 2^b-3, inasmuch as I have taken sub-section 2^b-3 as being 440 feet in length. Therefore the highway signal S in this case will be displayed for a period of twenty seconds.

In the above three cases, I have assumed each time that the train traveling through the sections 1-2 and 2-3 did so at a uniform rate of speed. Let us now assume a case where a train stops in the section 1-2 so as to consume three or four minutes before it reaches the point 2 after it had passed the point 1. During this interval, the device A has made a full forward movement to its reverse position and the motor M has been cut out at the point 23. Let us now say that this train advances and accelerates so that its speed by the time it reaches the point 2 is forty miles per hour and that it travels through the section 2-3 at this speed of forty miles per hour. The device A having to take 100 seconds of backward movement before the contact 53 is opened to deenergize the relay L, it is apparent that the device A would supply current to relay L all the time the train is traveling the section 2-3 and thus the highway signal S would never be rendered active to display a warning signal except as the train occupies 2^b-3. However, the train in traveling the sub-section 2-2^a will do so in about 15 seconds and therefore reach 2^a before the thermal relay TH has had time to close its contact 76 and thus as soon as the train shunts the relay H³, the relay L will become deenergized and thus the warning signal will become active.

In this case we have assumed that the train requires thirty seconds to travel the distance from 2^a to 3, and the result is that the highway signal S will be displayed, in this case, for a period of thirty seconds. In other words, if a train is delayed in the section 1-2 and then accelerates to some higher rate of speed in the section 2-3, the warning signal S is rendered active as soon as the train reaches the point 2^a

with the result that ample warning will be given by the signal S.

Again let us assume that a train enters the section 2-3 and stops to make switching movements in the sub-section 2-2^a. As soon as the device A has again returned to its normal position, the relay K will be energized from generator G through the contact 55 and relay K once up will be retained up through its own stick circuit even after the motor M has been cut out and generator G ceases to deliver current. With the relay K energized and contact 83 closed, the relay L is supplied with current from battery through the contact 83, as long as the train occupies either the sub-section 2-2^a or 2^a-2^b. When the train advances and enters the sub-section 2^b-3, the highway signal S will then become active to display a warning signal.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track intersected by a highway, a highway crossing signal located at the intersection, means for starting the operation of said signal at substantially the same interval of time before a train reaches the intersection regardless of the speed of the train, and other means to insure the operation of said signal for at least an equal interval of time notwithstanding a change in the speed of the train as it approaches said intersection.

2. In combination, a stretch of railway track intersected by a highway, a highway crossing signal located at the intersection, a first time measuring device for starting the operation of said signal at substantially the same interval of time before a train reaches the intersection regardless of the speed of the train, and a second time measuring device to insure the operation of said signal for a period at least equal to said interval of time notwithstanding a change in the speed of the train as it approaches said intersection.

3. In combination, a stretch of railway track intersected by a highway, a highway crossing signal located at the intersection, a first time measuring device set into operation when a train approaches the intersection, circuit means controlled by said device for starting the operation of said signal at substantially the same interval of time before a train reaches the intersection regardless of the speed of the train, a second time measuring device also rendered active by a train approaching the intersection, and means controlled jointly by said two time measuring devices to insure at least an equal interval of operation of said signal notwithstanding a change in the speed of the train as it approaches the intersection.

4. In combination, a stretch of railway track intersected by a highway, a highway crossing signal located at the intersection, a time measuring device, a first circuit means controlled by a train approaching said intersection to set into operation said time measuring device, a second circuit means controlled by said time measuring device for starting the operation of said signal at substantially the same interval of

time before a train reaches the intersection regardless of the speed of the train, and a timing means adapted to cooperate with said time measuring device to insure at least an equal interval of operation of said signal notwithstanding a change in the speed of the train as it approaches the intersection. 80

5. In combination, a stretch of railway track intersected by a highway, a highway crossing signal located at the intersection, a time measuring device having a member with a forward movement and a backward movement, and including a reversible motor to move said member through said forward and backward movements, means operating when a train approaches the intersection to energize the motor in a direction to move said member through the forward movement when the train passes one fixed point and to energize the motor in a direction to move the member through the backward movement when the train reaches a second fixed point, and means for setting said signal into operation when said member reaches a given point in its backward movement. 95

6. In combination, a stretch of railway track intersected by a highway, a highway crossing signal located at the intersection, a time measuring device including a motor element, and a generator element, means to set the motor element into operation when a train approaches the intersection for operating the time measuring device and to actuate the generator element, and a circuit supplied with current from said generator element and controlled by said time measuring device for starting the operation of said signal at substantially the same interval of time before a train reaches the intersection, regardless of the speed of the train. 105

7. In combination, a stretch of railway track intersected by a highway, a highway crossing signal located at the intersection, a time measuring device including a dynamotor element, means to set the dynamotor into operation when a train approaches the intersection for operating the time measuring device, and a circuit supplied with current from said dynamotor and controlled by said time measuring device for starting the operation of said signal at substantially the same interval of time before a train reaches the intersection regardless of the speed of the train. 110

8. In combination, a stretch of railway track intersected by a highway, a highway crossing signal located at the intersection, a track circuit effective to start the operation of said signal upon the approach of a train, a time measuring device having a normal and a reverse position, a motor element set into operation as a train passes one fixed point as it approaches the intersection for operating the time measuring device 135 away from normal position towards the reverse position and then as the train reaches a second fixed point reversing and returning said device to the normal position, means to render the track circuit ineffective to continue the operation of said signal when a train occupies a certain portion of the stretch after the time measuring device has been returned to its normal position, and a circuit controlled jointly by the motor element and the time measuring device to render effective said means. 140

9. In combination, a stretch of railway track intersected by a highway divided into two track sections on one side of the highway, a track relay for each track section, a highway crossing 150

- signal located at the intersection, a controlling circuit for said signal including a front contact of the track relay for the track section closer to the highway; a time measuring device including a generator element, a motor element for operating said time measuring device and said generator, and a normally open circuit controller adapted to be closed at a given point in the movement of the device; a circuit for controlling the operation of the motor element jointly controlled by the track relay of each of the track sections, and a shunt for said signal controlling circuit around said relay contact and including said circuit controller and said generator.
- 10 13. In combination, a stretch of railway track intersected by a highway, a highway crossing signal located at the intersection, a track circuit responsive to the presence of a train to set into operation said signal, a motor operated time measuring device having a normal position and adapted when moved a predetermined amount away from said normal position to render the track circuit ineffective to set into operation said signal, a circuit controller actuated by said time measuring device and closed only when said device occupies its normal position, and a controlling circuit responsive to a train approaching the intersection to set into operation the motor of said time measuring device to move said device away from its normal position, and said circuit including said circuit controller and effective only when said circuit controller is closed.
- 15 14. In combination, a stretch of railway track intersected by a highway, a highway crossing signal located at the intersection, a track circuit responsive to the presence of a train to set into operation said signal, a motor operated time measuring device having a normal position and adapted when moved a predetermined amount away from said normal position to render the track circuit ineffective to set into operation said signal, and means effective only upon the condition that said time measuring device occupies its normal position to set into operation the motor to move the device away from said normal position in response to a train approaching the intersection.
- 20 15. In combination, a stretch of railway track intersected by a highway, a highway crossing signal located at the intersection, a track section located on one side of the highway, a track relay for said track section, a controlling circuit including a front contact of the track relay to set the signal into operation as a train enters the track section, a thermal relay energized as a train approaches the intersection, and means controlled by the thermal relay to close a shunt around the said front contact.
- 25 16. In combination, a time measuring device including a circuit controller, a current generating element and a motor element, said motor element adapted to actuate said circuit controller and said current generating element, and a signaling circuit including said circuit controller and arranged to be supplied with current from the generating element during a predetermined time interval of the operation of said time measuring device.
- 30 17. In combination, a stretch of railway track intersected by a highway, a highway crossing signal located at the intersection, means for setting said signal into operation when a train approaching the intersection reaches a fixed point, means including a timing device for delaying the operation of the signal, and means controlled by said timing device for cutting said delaying means out of service in the event of failure of the timing device.
- 35 18. In combination, a stretch of railway track intersected by a highway, a highway crossing signal for the intersection, a member normal-

ly occupying a given position, means for moving said member away from said given position during the time interval required for a train approaching said highway to traverse a fixed distance, means effective when the train has traversed said fixed distance to restore said member to its given position at a predetermined rate, means controlled by said member for starting the operation of said signal at the end of a variable time interval after the train has traversed such fixed distance, which time interval depends upon the distance said member has been moved away from the given position, and means for starting the operation of said signal as soon as the train has traversed such fixed distance in the event of failure of said member to be returned to its given position at said predetermined rate.

19. In combination, a stretch of railway track intersected by a highway, a highway crossing signal for the intersection, means for setting said signal into operation when a train approaching the intersection reaches a fixed point, a timing device controlled by the speed of the train and normally operating at a predetermined rate for delaying the operation of the signal, and means for rendering said device ineffective to delay the operation of said signal in the event of failure of the device to operate at such predetermined rate.

20. In combination, a stretch of railway track intersected by a highway, a highway crossing signal for the intersection, a timing device having a forward and a backward movement, means set into operation as a train passes one fixed point as it approaches the intersection for operating the timing device in its forward movement and for initiating the backward movement of said device when the train reaches a second fixed point, means governed by the backward movement of the timing device to determine the time of starting the operation of the signal, and means rendered effective by the first said means during its backward movement to at once start the operation of the signal in the event of a failure of the first said means to function.

21. In combination, a stretch of railway track intersected by a highway, a highway crossing signal located at the intersection to be exhibited as a train approaches the intersection, a time measuring means governed both by the speed of a train and by changes in the speed of the train as it approaches the intersection, and circuit means controlled by said time measuring means for establishing the exhibit of said signal.

22. In combination, a stretch of railway track intersected by a highway, a highway crossing signal located at the intersection, traffic controlled means for causing the exhibit of said signal as a train approaches the intersection, time measuring means governed both by the speed of the train and by changes in the speed of the train as it approaches the intersection to influence the traffic controlled means and thereby determine the interval for exhibiting said signal.

23. In combination, a stretch of railway track intersected by a highway, a highway crossing signal located at the intersection, means for causing the exhibit of said signal upon the approach of a train to the intersection, and means for governing the time of starting the exhibit of said signal influenced by changes in the speed of the train as it approaches said intersection.

24. In combination, a stretch of railway track intersected by a highway, a highway crossing signal for the intersection, a member normally occupying a given position, means for moving said member away from said given position during the time interval required for a train approaching said highway to traverse a fixed distance, means effective when the train has traversed said fixed distance to restore said member to its given position at a predetermined rate, means controlled by said member for starting the operation of said signal at the end of a variable time interval after the train has traversed such fixed distance, which time interval depends upon the distance said member has been moved away from the given position, and means for starting the operation of said signal after the train has traversed such fixed distance in the event of failure of said member to be returned to its given position at said predetermined rate. 95

25. In combination, a stretch of railway track intersected by a highway, a highway crossing signal for the intersection, a timing device having a forward and a backward movement, means set into operation as a train passes one fixed point as it approaches the intersection for operating the timing device in its forward movement and for initiating the backward movement of said device when the train reaches a second fixed point, means governed by the backward movement of the timing device to determine the time of starting the operation of the signal, and means rendered effective by the first said means during its backward movement to start the operation of the signal in the event of a failure of the first said means to function. 100

26. In combination, a stretch of railway track intersected by a highway, a highway crossing signal located at the intersection, a track circuit responsive to the presence of a train approaching said intersection to set said signal into operation, a slow acting device having a normal position and adapted when moved a predetermined amount away from said normal position to render the track circuit ineffective to set said signal into operation, actuating means for moving said slow acting device, and means responsive to a train approaching the intersection before it reaches said track circuit for setting said actuating means into operation if and only if said slow acting device occupies its normal position. 115

27. In combination, a stretch of railway track intersected by a highway, a highway crossing signal located at the intersection, a first and a second track section traversed successively by a train approaching said intersection, a track circuit including a track relay for each track section, controlling means governed by the track relay of the second track section for starting operation of said signal as a train enters said second section, a device having a normal position and arranged to actuate an operating contact when moved a predetermined amount away from said starting position, a normally deenergized motor for moving said device, a normally deenergized operating relay; a circuit for said operating relay including a front contact of the track relay of the second section, a back contact of the track relay of the first section and a contact closed only when said device is in its normal position, a circuit including a front contact of the operating relay to energize said motor, and means including said operating contact and a contact governed by said operating relay for 120

rendering the track relay of the second section ineffective to cause said controlling means to set said signal into operation.

28. In combination, a stretch of railway track intersected by a highway, a highway crossing signal located at the intersection, a time measuring device including a motor element and a circuit controller element, means to set the motor element into operation when a train approaches the intersection to actuate the circuit controller element, a circuit governed by said circuit controller element for starting the operation of said signal at substantially the same interval before a train reaches the intersection regardless of the speed of the train, and a source of current for said circuit rendered available when and only when the motor element is in operation.

29. In combination, a stretch of railway track intersected by a highway, a highway crossing signal located at the intersection, a time measuring device including a motor element and a circuit controller element, means to set the motor element into operation when a train approaches the intersection to actuate the circuit controller element, a circuit governed by said circuit controller element for starting the operation of said signal at substantially the same interval before a train reaches the intersection regardless of the speed of the train, and means to render said circuit effective when and only when the motor element is in operation.
